TRACTION APPARATUS

Homer D. Peachey, Lewistown, Pa.

Application May 22, 1937, Serial No. 144,236

2 Claims. (Cl. 128—84)

This invention appertains to new and useful improvements in traction apparatus such as is employed in maintaining fractures reduced to permit healing.

5 The principal object of the present invention is to provide an apparatus of the character stated which can be readily adjusted to meet substantially all conditions of the patient.

Another important object of the invention is 10 to provide an apparatus of the character stated which can be employed for exerting traction on fractured legs, arms, or necks.

Another important object of the invention is 15 to provide an apparatus which can be quickly adjusted and which will remain in adjusted position against accidental self-adjustment.

Still another important object of the invention is to provide a traction apparatus which can be placed next to a bed and actually braced by the 20 bed without touching any painted part of the bed, thus eliminating the likelihood of defacing the bed in any way.

Other important objects and advantages of 25 the invention will become apparent to the reader of the following specification.

In the drawings:

Figure 1 is a side elevational view of the apparatus.

Figure 2 is a front elevational view.

30 Figure 3 is a top plan view on line 3—3.

Figure 4 is a vertical sectional view.

Figure 5 is a top plan view of the super assembly.

35 Figure 6 is a sectional view on the line 6—6 of Figure 1.

Figure 7 is a sectional view on line 7—7 of Figure 4.

Figure 8 is a sectional view on the line 8—8 of Figure 1.

40 Figure 9 is a sectional view on the line 9—9 of Figure 1.

Figure 10 is a sectional view on the line 10—10 of Figure 1.

Figure 11 is a side elevational view of the apparatus shown used with a Russell splint structure.

Figure 12 is a side elevational view of the apparatus in use on an arm fracture.

Figure 13 is a side elevational view of the device 50 adapted for use on neck structures.

Referring to the drawings, wherein like numerals designate like parts, it can be seen that the apparatus consists of the base 5 from which the socket member 6 extends. The socket member 55 8 receives the lower end of the tubular upright 7 in which slides the lower portion of the post 8. A collar 9 is provided around the upper portion of the upright 7 and a set screw 10 is provided in conjunction therewith for fixing the said post 60 8 at the proper elevation.

A hub-like structure 11 is provided at the upper end of the post 8, the same having an inwardly tapering pocket at each side thereof. The bottom of the pocket at the back side of the hub structure 11 has the threaded pin 12 extending therethrough and through the annular and tapered plug 13, which has a central opening for receiving the pin 12. A knob-like nut 14, is feedable on the pin 12 and against the tapered plug 13 to urge the plug 13 into the pocket on the adjacent side of the hub structure 11 for firmly wedging the same in place. The plug 13 has a gooseneck shaped arm 15, the upper end of which is secured between a pair of ears 16 by the screw 17 passing through the ends of the clamp band 18. This clamp band surrounds the lower portion of the barrel 19 in which the rod 20 is slidable. The upper end of the barrel 19 is longitudinally slotted as at 21 and a clamp band 22 surrounds this portion and is provided with the set screw 23 which can be operated to tighten the band in place and contract this portion of the barrel 19 to hold the rod 20 in adjusted position with respect to the said barrel.

The upper end of the rod 20 is provided with the yoke 24 through which the headed bolt 25 extends. This bolt extends through the adjacent end of the brace arms 26—26 which originally extend from the cross member 27 of the main frame and also through the adjacent end of the arms 28—28 between the outer ends of which the pulley 29 is mounted. Furthermore, the headed pin 25 passes through the pulley 30 which is situated between the outer ends of the arms 26—26 and the knurled nut 31 is provided on this nut for tightening these bars together in proper adjusted position.

The cross member 27 is provided with openings in the ends thereof for receiving the upright members 32—32 of the main frame, these upright members rising from the said hub-like structure 11. The cross member 27 is provided with set screws 33 at its ends, each notched for receiving the corresponding upright members 32 so that when the set screws 33 are moved in one direction or the other, the ends of the notched portions will bind against the uprights 32 and firmly hold the cross member 27 in the desired position.

Pin members 34—34 are slidable in the upper end portion of the upright members 32—32 and each is provided with a laterally disposed tapered head 35 for engagement into an internally tapered cup member 36. The cup member is provided with an opening through which the threaded shank 37 of the head 35 passes and a knurled nut 38 on this threaded shank 37 can be fed inwardly against the cup 36 to bind the cup on the head 35. Extending from each of the cup-shaped members 36 is an arm 39 while bridging the pins 34 is the cross bar 40. An arm 41 having one 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

end bifurcated to receive the cross bar 40 is provided at this point with a set screw 42 to prevent displacement of the arm, while the opposite end is provided with a yoke in which the pulley 43 is mounted.

The arms 39 at their remaining ends are provided with internally tapered cup members 44 for receiving the tapered head members 45 of additional arm members 46. Each of these head members 45 is provided with a threaded shank 47 disposed through an opening in the corresponding cup-shaped member 44. Each of these shanks 47 is provided with a knurled nut 48 whereby the cup-shaped member 44 can be wedged onto the corresponding head 45.

Between the converging end portions of the arms 46 is disposed the parallel bars 49-49. Furthermore, it can be seen in Figure 1, that rising from the cup-shaped members 44 are additional arms 50 which taken with the arms 46 serve as braces for the said bars 49-49 and between these bars 49-49 are mounted the pulleys 51, 52, 53, 54, and 55.

Reverting back to the hub-like structure 11, it can be seen that an anchoring extension or brace generally referred to by numeral 56 is employed and this consists in the provision of a pair of horizontally disposed trunnions 57-57 extending laterally from the plug-like structure 58 which has one end tapered for disposition into the tapered pocket on the front side of the hub-like structure 11. A threaded pin 59 extends from the bottom of this particular pocket and through the plug 58 and is equipped with the knob-like nut 60. By tightening this nut against the plug 58, the plug can be jammed into the hub-like structure 11.

Internally tapered cap-like members 61-61 are provided on the outer ends of the trunnions 57-57 and set screws 62 are disposed through openings in these caps and into the recesses in the trunnions 57-57 for binding these internally tapered cap members 61 onto the trunnions 57.

Extending from each of the cap-shaped members 61 is a rod 63 engaged into the adjacent end portion of an elongated tubular leg member 64. As is shown in Figure 3, these leg members 64 are connected together by struts 65 at desired intervals.

The inner ends of the tubular legs 64 are slit as at 66 and clamp means 67 are provided at these ends of the legs 64 by clamping the legs in adjusted position on the rods 63. Thus this anchor or brace is constructed for interposition between the mattress and spring of a bed so as to rigidify the apparatus when it is being employed.

It can be seen in Figure 3, that the base 5 can be provided with indentations 5a to accommodate the legs of a bed when the apparatus is to be set closely to the bed.

As shown in Figure 11, in using the Russell splint for leg fractures, the foot is taped as at 69 and a cable 70 extends from this and over the pulley 51 to support the weight 70. A stirrup 71 is provided with the knee portion of the leg and from this extends the cable 72 which passes over the pulley 52 and over the pulley 43 and then over a pulley 73 attached to the foot, and then outwardly over the pulley 30, where it extends downwardly for supporting the weight 74. In this connection the super assembly of the apparatus can be adjusted to any desired elevated or des-

cended position and suitable adjustment can be made to accommodate the particular size of person and his posture.

In the case of an arm fracture as shown in Figure 12, the splint has the cable 75 attached thereto and this extends outwardly and over the pulley 30 and downwardly to the weight 76. The hand is held elevated and provided with the spreader 77 from which extends the cable 78 to pass over the pulley 54 and then downwardly 10 over the pulleys 43 and 30 to the weight 79.

In the case of neck fractures, the chin and occiput straps 80-81 are applied to the head and from this extends the cable 82 to pass over the pulley 30 and downwardly to the weight 83.

The pulleys and adjustments can be used in various other positions and adaptations to take care of various other conditions for treatment.

While the foregoing specification sets forth the invention in specific terms, it is to be understood that numerous changes in the shape, size, and materials may be resorted to without departing from the spirit and scope of the invention as claimed hereinafter.

Having thus described the invention, what is claimed as new is:

1. Traction apparatus for use with a weighted cable comprising a base, a column arising from the base, a pulley rack including a plurality of peripherally spaced pulleys for training of the cable thereover selectively and adapted for location above and to one side of the column in angular position relative to the latter, means to mount said rack on said column including a frame upstanding from the column and pivotally mounted at the lower end thereof for inclining into different set positions, a V-shaped mounting supporting said rack, a pair of laterally spaced bracket arms pivoted at opposite ends thereof to the upper end of said frame and to said mounting, respectively, and a plurality of pulleys mounted on said frame for training thereover of the cable from the pulley rack selectively.

2. Traction apparatus for use with a weighted cable comprising a base, a column arising from the base, a pulley rack including a plurality of peripherally spaced pulleys for training of the cable thereover selectively and adapted for location above and to one side of the column in angular position relative to the latter, means to mount said rack on said column including a frame upstanding from the column and pivotally mounted at the lower end thereof for inclining into different set positions, a V-shaped mounting supporting said rack, a pair of laterally spaced bracket arms pivoted at opposite ends thereof to the upper end of said frame and to said mounting, respectively, a plurality of pulleys mounted on said frame for training thereover of the cable from the pulley rack selectively, and means to anchor said frame and column to a bed comprising a leg including a pair of side sections connected together in spaced apart parallel relation and adapted to be interposed flat between the mattress and springs of the bed, said sections being extensible to regulate the length thereof, and said leg having a swiveled connection at one end thereof with said frame for compensating movement of the leg about relatively rightangled axes under flexing of said springs.

HOMER D. PEACHEY.
